A. K. Sanders, & M. S. Wedder, of New York, N.Y.
Assignors to A. K. Sanders, of Troy, N.Y.
Letters Patent No. 1295, dated July 31, 1860.

The schedule referred to in these Letters Patent, and making part of the same -

To all whom it may concern:

Be it known that we, A. K. Sanders, of the City, County, and State of New York, and M. S. Wedder, of the City of Troy, in the County of Rensselaer, and State aforesaid, have jointly invented or produced a new and original design for Cooking Ranges, and we do hereby declare that the following is a full and exact description of the same, reference being had to the annexed photographic drawing which represents the ornamental front plates of our said design, and which forms a part of this Specification.

Our new design consists in the arrangement, upon the front plates of a Cooking Range, of the stone work imitation columns, a, at the extreme ends of the front; - the shield-like ornament, b, in the middle, and the fan-like ornaments, c, in the four corners, of the arched-top panels surrounded by the ornamental border, d, of each of the two oven doors; - the ornamental shield, e, on the middle of the rectangular panel surrounded by the ornamental moulding, f, of each of the two lower fire doors; and the ornament, g, in the middle of the oblong panel surrounded by the ornamental border moulding, f, on each of the two upper fire doors, and the scrolls, h, h, over the two ovens; all shaped and

disposed as represented in the annexed photographic drawing.-

What we claim as our joint invention, or production and desire to secure by Letters Patent, is the ornamenting of the front plates of a working Range, in the manner above described.
